UNITED STATES PATENT OFFICE.

FREDERIC TUDOR AND QUIMBY N. EVANS, OF BOSTON, MASSACHUSETTS.

STEAM-RADIATOR.

SPECIFICATION forming part of Letters Patent No. 224,055, dated February 3, 1880.

Application filed September 18, 1877.

To all whom it may concern:

Be it known that we, FREDERIC TUDOR and QUIMBY N. EVANS, both of Boston, in the county of Suffolk and State of Massachusetts, 5 have invented an Improvement in Steam-Radiators, of which the following is a specification.

This invention relates to steam-radiators; and it consists in the combination, with a section 10 of a radiator, of attached hollow steam-legs adapted to fit openings in a radiator-base, and fastened thereto by tap-bolts which serve to draw the section and base together; also, in the combination, with the cast-iron section, of 15 a base having a central air-space, the lower portion of the section being placed across the opening of the air-space to permit the air to impinge against the bottom of the section and circulate freely among the pipes; also, in the 20 combination, with a steam-radiator, of an inclosing-case adapted to be supplied with air from within or outside of the building, and provided with a register to regulate the quantity of heated air to be admitted into the 25 room.

Figure 1 represents a sectional top view of one of our radiators placed within a case, the section being on the line *x x*, Fig. 2; Fig. 2, a vertical section thereof on the line *y y*, Fig. 1; 30 and Fig. 3, a vertical section on line *z z*, Fig. 1.

The hollow cast-iron pipes *a a* composing each section—preferably from six to twelve pipes—are cast as integral parts of the steam-chambers *b c*, such chambers connecting the 35 ends of the pipes.

Each steam-chamber *c* is provided with hollow steam-legs *d*, provided at their lower ends with screw-threads to be engaged by a tap-bolt, *e*, inserted through the base *f*, to enable 40 the section to be held in close contact or steam-tight with relation to the base.

The steam-chamber *b* is bored to receive the hollow steam-supplies *g*, projecting from the 45 hollow shell *h'* of the evaporating-pan *h*, so as to afford free circulation of steam from the chamber through the hollow portion of the pan.

The base *f* is provided with an open central air-space, *i*, directly across which the base 50 of each section is placed, as shown in the drawings, so that air rising through such air-space meets the lower end of the section and

circulates freely upward. Allowing the air to pass in this way in contact with the entire 55 section heats it more effectually than if the air merely passed upward between the sections.

Casting the sections in one piece, but with separated pipes, and connecting the sections with the base, as described, enables the production of a radiator at a much less price than 60 if the legs or pipes were screwed independently to the base, as heretofore common.

The case *j*, surrounding the radiator, has an inlet, *k*, to receive air from without the building, and an inlet, *l*, to receive air from the apartment in which the case is placed. A register, *m*, controls the openings of these two inlets, and determines which shall admit air into the casing. This casing is also provided 70 with a register, *n*, with an air-space, *o*, and with air-passages *p q r*.

When the register is placed to close the air-passage *r*, the air admitted to the case circulates freely over the radiator and out through 75 the passages *p* and *q*.

When register *n* is closed *r* will be open, and the admitted air passes beneath the radiator through passage *r*, space *o*, and passage *q*.

The mean temperature of the air discharged 80 at *q* will depend upon the position of the register *n* with relation to the passages *p* and *r*.

We claim—

1. A steam-radiator section composed of 85 hollow tubes and steam-chambers, cast together, as described, and provided with hollow steam-legs, in combination with a radiator-base and tap-bolts, substantially as described.

2. The combination, with the cast-iron section, of a base provided with a central opening, the bottom of the section being extended directly across such opening, substantially as 90 and to operate as described.

3. The combination, with a steam-radiator, of an inclosing-case provided with passages *k l r p q*, and with registers *m n* and air-space 95 *o*, to operate substantially as described.

In testimony whereof we have signed our names to this specification in the presence of two subscribing witnesses.

FREDERIC TUDOR.
QUIMBY N. EVANS.
